OPERATING AND CONTROLLING MECHANISM FOR HYDRAULIC BARBER CHAIRS

Application filed May 7, 1928. Serial No. 275,677.

This invention relates to chairs of the type commonly referred to as "hydraulic barber chairs", and particularly to the means used in such chairs for operating the pump plunger and for releasing the clamp associated with a reclining bar that holds the back and apron of the chair in adjusted position.

One chair of the general type mentioned, that is now in commercial use, is equipped with a seat frame attached to the upper end of a hollow stem which reciprocates in a stationary socket in the base of the chair. A pump plunger, which is reciprocatingly mounted in the stem, is used to effect and control the circulation of a non-compressible liquid to raise and lower the stem which carries the seat frame, and a handle or operating lever is used to actuate said pump plunger. When it is desired to raise the seat frame the operating handle is rocked back and forth so as to impart short strokes to the pump plunger, and thus cause charges of liquid to be forced from the stem into the socket, thereby exerting upward pressure on the stem, and when it is desired to lower the seat frame, a full stroke is imparted to the operating handle, so as to move the pump plunger into such a position that it will open a valve and permit the liquid in the socket to pass upwardly through by-pass ports into the stem, with the result that the stem and the seat frame connected to same move downwardly by gravity. The back and apron of the chair are held in adjusted position by a spring-pressed clamp which acts on a part, commonly termed a reclining bar, which clamp is released or rendered inoperative by pulling upwardly on the hand grip of the handle and then rocking the handle in a direction parallel to the side edge of the seat frame.

My invention consists of a novel means for coupling the operating handle of a hydraulic barber's chair of the general type mentioned with the rock shaft that actuates the pump plunger, and for transmitting movement from said handle to the reclining bar clamp so as to release the reclining bar, one object of the invention being to provide an operating and controlling mechanism

whose parts are of such design and arrangement that the mechanism is particularly adapted for use on a chair whose seat frame has a relatively great range of vertical movement and is capable of being moved downwardly to a lower level than is customary with conventional hydraulic barbers' chairs.

Another object is to provide an operating and controlling mechanism for hydraulic barbers' chairs, which is of such design that the reclining bar clamp can be released simply by pushing the upper end of the handle inwardly towards the seat frame, followed by a slight rocking movement of said handle parallel to the side edge of the seat frame.

And still another object of the invention is to provide a controlling and operating mechanism for hydraulic barbers' chairs that is of rugged construction and of such design that it is not necessary to form an opening in the flange of the seat frame of the chair to receive any parts of said mechanism, even though the seat frame is equipped with a relatively deep flange. Other objects and desirable features of my invention will be hereinafter pointed out.

Figure 1 of the drawings is a side elevational view of a barber's chair equipped with a controlling and operating mechanism constructed in accordance with my invention.

Figure 2 is a transverse sectional view through the seat frame, with the stem and some of the parts of the mechanism broken away so as to more clearly illustrate the construction of same.

Figure 3 is a detail view, illustrating how the clutch between the handle and the rock shaft is tripped or rendered inoperative by exerting a slight inward thrust on the upper end of the handle.

Figure 4 is a similar view, showing how a slight rocking movement of the handle after said clutch has been tripped causes the reclining bar clamp to be released.

Figure 5 is a top plan view of the stem, with the seat frame removed.

Figure 6 is a detail sectional view, taken on the line 6—6 of Figure 2, looking in the direction indicated by the arrows.

Figure 7 is a view similar to Figure 6,

showing the position which the parts assume when the handle is being rocked to impart short strokes to the pump plunger.

Figure 8 is a view similar to Figure 6 showing the position which the parts assume when a full stroke is imparted to the handle so as to cause the stem and seat frame to descend.

Figure 9 is a view similar to Figure 6, showing the position which the parts assume when the operating handle is rocked to release the reclining bar clamp.

Figure 10 is a sectional view, taken on the line 10—10 of Figure 2, looking in the direction indicated by the arrows; and

Figure 11 is a sectional view, taken on the line 11—11 of Figure 2, looking in the direction indicated by the arrows.

Referring to the drawings which illustrate the preferred form of my invention, A designates the seat of a conventional barber's chair, B designates the stem which carries the seat frame, C designates the base that holds a socket or cylinder which receives the stem; B; D designates the plunger, shown in broken lines in Figure 1, that is used to force charges of liquid from the stem into the socket to cause the stem to move upwardly, and also used to trip the valve which permits the liquid to pass from the socket upwardly into the stem when it is desired to lower the seat of the chair; E designates a horizontally-disposed rock shaft mounted at the upper end of the stem underneath the seat frame and provided with a crank arm E', and F designates a link that joins said crank arm to the plunger D. The chair is equipped with a back G and an apron H that are combined with the seat in such a way that the back can be arranged in a reclined position, as shown in broken lines in Figure 1; and said back and apron are held in adjusted position by means of a reclining bar I that is connected to the apron and which co-operates with a clamp composed of two jaws or elements J and J' between which the reclining bar passes, as shown in Figure 2. Movement is imparted to the rock shaft E so as to actuate the pump plunger D, and movement is imparted to one jaw or element of the reclining bar clamp so as to release the reclining bar, by means of an operating handle or lever K.

The handle K is arranged at one side of the seat frame of the chair and is provided at its lower end with a horizontally-disposed portion 1 which projects inwardly under the seat frame. At the inner end of the horizontally-disposed portion 1 of said handle is an upwardly-projecting, bifurcated portion 2 that is pivotally connected by a pivot pin 3 to a bearing 4 which is mounted on the rock shaft E in such a way that it is free to oscillate on said shaft and also move longitudinally of said shaft. Normally, the bearing 4 is prevented from turning or os-

cillating relatively to the shaft E by a clutch formed by a lug 5 carried by the upwardly-projecting portion 2 of the handle, and a notch 6 formed in a collar 7 that is secured by a pin 8 or in any other suitable manner, to the rock shaft E, adjacent the point where the outer end of said rock shaft is journaled in a bearing on the bracket 9 that projects laterally from the plate 10 at the upper end of the stem to which the seat frame is connected. When the lug 5 is arranged in the notch 6 in the collar 7 the handle K will be operatively connected to the rock shaft E in such a way that a rocking movement imparted to said handle in a direction parallel to the adjacent side edge of the seat frame of the chair will cause the shaft E to rock, and thus reciprocate the plunger D. If it is desired to raise the seat frame the operator rocks the handle K back and forth, as indicated in Figures 6 and 7; so as to impart short strokes to the plunger D, thereby causing the liquid in the stem to be forced downwardly into the socket. If it is desired to lower the seat frame, the operator imparts a full forward stroke to the handle K, as indicated in Figure 8, thereby causing the plunger D to trip the valve which permits the liquid to flow upwardly through the by-pass ports from the socket into the stem. In order to assist the operator in manipulating the handle K properly in the operation of lowering the seat frame, the bearing 4 on which the handle is pivoted is provided with a spring-pressed buffer 11 that is adapted to strike against the bracket 9, thus offering some resistance to the movement of the handle, when a full forward stroke is imparted to the handle, thereby notifying the operator that the handle has been pushed into a position to release the valve which permits the liquid to pass upwardly from the socket into the hollow stem of the chair.

As previously stated, the reclining bar clamp is composed of two elements or jaws J and J'. These jaws are pivotally connected together by a pivot 12 arranged above recesses in the meeting faces of the jaws that receive the reclining bar I, and said jaws are combined in such a way as to form a single unit that is rockably mounted on the rock shaft E, at one side of the stem B of the chair. The jaw J' is capable of rocking or swinging towards and away from the co-operating stationary jaw J, and expansion springs 13 are interposed between said jaws above the pivotal connection 12 between the same so as to normally hold said jaws pressed tightly against the reclining bar. When it is desired to release the reclining bar, preparatory to changing the position of the back and apron of the chair, the operator exerts pressure on the upper end of the handle K inwardly towards the seat frame of the chair, thereby rocking said handle on its pivot 3

into the position shown in Figure 3, which operation causes the lug 5 on the upwardly-projecting portion 2 at the lower end of the handle to be withdrawn from the notch in the collar 7 on the rock shaft E, thereby unclutching the handle K from the rock shaft E. The operator then swings the upper end of the handle K to the left, looking at Figures 1 and 9, so as to cause an inclined surface 5^a 5 on the outer end of the lug 5 to engage and travel over a cam surface 7^a on the inner side of the collar 7. The pressure which said cam surface exerts on the lug 5 during this rocking movement of the handle K causes the bearing 4 to shift longitudinally of the rock shaft E from the position shown in Figure 3 into the position shown in Figure 4, thereby causing said bearing 4 to exert pressure on the movable jaw J' of the reclining bar 10 clamp in a direction to move said jaw into the position shown in Figure 4, thus releasing the reclining bar. During the operation of adjusting or changing the position of the back and apron the reclining bar clamp is effectively retained in its released or open 15 position by the engagement of the cam 7^a on the collar 7, with the lug 5 on the handle K. To render the reclining bar clamp operative it is only necessary to restore the handle K 20 to its normal upright position, and as soon as the lug 5 comes into alignment with the notch 6 in the collar 7, the pressure which the springs 13 of the reclining bar clamp exert on the movable jaw J' causes the bearing 4 to shift longitudinally of the shaft E 25 in the opposite direction, back into the position shown in Figure 3.

In an hydraulic barber's chair operating and controlling mechanism of the kind described it is only necessary for the operator to give the handle K a slight inward push towards the seat frame of the chair, followed by a slight rocking movement parallel to the side edge of the seat frame, in order to release 30 the reclining bar. Movement is imparted to the pump plunger D to raise and lower the seat frame by manipulating the handle K in the same manner as in the conventional barber's chair. The parts of the mechanism are of simple design and they are so compactly arranged that the mechanism is particularly adapted for use on a chair whose seat frame is capable of moving downwardly to a lower level than is the usual 35 custom, and another desirable feature of such a mechanism is that it is of such design that no part of same has to pass through the depending flange on the seat frame of the chair, even when the seat frame is equipped with 40 an exceptionally deep flange.

Having thus described my invention, what I claim as new and desire to secure by Letters Patent is:

1. In an hydraulic barber's chair of the 45 type that comprises a vertically-movable stem

and a reclining back, a reciprocating plunger for effecting the raising and lowering of said stem, a reclining bar and a co-operating clamp for holding the back in its adjusted position, a rock shaft operatively connected with said plunger, a handle for actuating said rock shaft to impart movement to the plunger, a shiftable bearing on which said handle is pivotally mounted, co-operating clutch members on said shaft and handle adapted to be disengaged by rocking said handle on its pivot, and means whereby a slight oscillatory movement of said handle after it has been disengaged from said shaft causes said bearing to exert pressure on the reclining bar clamp in a direction to release the reclining bar.

2. In an hydraulic barber's chair of the type that comprises a vertically-movable stem and a reclining back, a reciprocating plunger for effecting the raising and lowering of said stem, a reclining bar and a co-operating clamp for holding the back in its adjusted position, a rock shaft operatively connected with said plunger, a handle for actuating said rock shaft to impart movement to the plunger, a bearing mounted loosely on said rock shaft, a handle pivotally connected to said bearing, a clutch member on said shaft, a co-operating clutch member on said handle that is adapted to be disengaged from the clutch member on the shaft by rocking said handle on its pivot, and co-operating surfaces on said clutch members for causing said bearing to move longitudinally of said shaft and exert pressure on the reclining bar clamp in a direction to release the reclining bar when said handle is moved in a direction to cause said bearing to turn on said shaft.

3. In an hydraulic barber's chair of the type that comprises a vertically-movable stem and a reclining back, a plunger for effecting the raising and lowering of said stem, a reclining bar and a co-operating clamp for holding the back in adjusted position, a rock shaft for operating said plunger arranged horizontally at the upper end of said stem beneath the seat frame of the chair, a bearing mounted on said shaft and adapted to oscillate and also shift longitudinally of said shaft, a handle provided at its lower end with a portion that projects under the seat frame of the chair and which is provided with an upwardly-projecting part that is pivotally connected to said bearing, a clutch member connected to said upwardly-projecting part, a co-operating clutch member connected to said rock shaft, and a cam on one of said clutch members that causes said bearing to exert pressure on the reclining bar clamp in a direction to release the reclining bar when said handle is oscillated about said rock shaft as an axis after said clutch members have been disengaged.

4. In an hydraulic barber's chair of the type that comprises a vertically-movable stem that carries the seat frame, a reclining back, a plunger for effecting the raising and lowering of the stem and the seat frame thereon, a rock shaft for operating said plunger arranged horizontally at the upper end of the stem beneath the seat frame, a reclining bar for governing the position of the back, a 5 spring-pressed clamp for holding said reclining bar against movement rockably mounted on said rock shaft, a bearing loosely mounted on said rock shaft at one side of said clamp, a handle provided at its lower end 10 with a portion that projects inwardly under the seat frame and which is provided with an upwardly-projecting, bifurcated part that is pivotally connected to said bearing, a collar connected to said rock shaft and provided with a notch, a lug on the bifurcated part of the handle that is adapted to enter 15 said notch, and a cam on said collar for causing said bearing to exert pressure on the reclining bar clamp in a direction to release 20 the reclining bar when said handle is oscillated about said rock shaft as an axis after the lug on said handle has been disengaged 25 from the notch in said collar. 5. In an hydraulic barber's chair of the 30 type that comprises a vertically-movable stem and a reclining back, a reciprocating plunger for effecting the raising and lowering of said stem, a reclining bar and a co-operating clamp for holding the back in its 35 adjusted position, a rock shaft operatively connected with said plunger, a handle for actuating said rock shaft to impart movement to the plunger, a shiftable bearing on 40 said rock shaft on which said handle is pivotally mounted for swinging movement longitudinally of the rock shaft, a clutch for connecting said handle with said rock shaft, provided with means for causing said clutch to be rendered inoperative when said handle 45 is rocked in one direction on its pivot, and means whereby an oscillatory movement of said handle after said clutch has been rendered inoperative, causes the reclining bar to be released from its clamp. 50 6. In an hydraulic barber's chair of the 55 type that comprises a vertically-movable stem and a reclining back, a reciprocating plunger for effecting the raising and lowering of said stem, a reclining bar and a co-operating clamp for holding the back in its 60 adjusted position, a rock shaft operatively connected with said plunger, a handle for actuating said rock shaft to impart movement to said plunger, a shiftable bearing on 65 which said handle is pivotally mounted, a clutch for connecting said handle to said rock shaft, provided with means whereby a slight inward movement of the upper end of said handle towards the seat frame of the chair 70 renders the clutch inoperative and releases 75 said handle from said rock shaft, and means whereby an oscillatory movement of the handle relatively to said rock shaft, after the clutch has been rendered inoperative, causes the reclining bar clamp to be released. 80 LIONEL A.
